US00D614207S

(12) **United States Design Patent**
Ruvang

(10) **Patent No.:** **US D614,207 S**
(45) **Date of Patent:** ** *Apr. 20, 2010

- (54) **GROUND ENGAGING WEAR MEMBER**
(75) Inventor: **John A. Ruvang**, Lake Dallas, TX (US)
(73) Assignee: **Hensley Industries, Inc.**, Dallas, TX (US)
(**) Term: **14 Years**
(21) Appl. No.: **29/343,321**
(22) Filed: **Sep. 10, 2009**

Related U.S. Application Data

- (62) Division of application No. 29/298,828, filed on Dec. 13, 2007, now Pat. No. Des. 602,505.

(57) **CLAIM**

The ornamental design for a ground engaging wear member, as shown and described.

DESCRIPTION

FIG. 1 is a perspective view of the ground engaging wear member showing my new design according to a first embodiment;

FIG. 2 is another perspective view of the first embodiment; FIG. 3 is an elevational view of the first embodiment; FIG. 4 is a sectional view of the first embodiment taken along line 4—4 of FIG. 1; FIG. 5 is a sectional view of the first embodiment taken along line 5—5 of FIG. 2; FIG. 6 is a sectional view of the first embodiment taken along line 6—6 of FIG. 1; FIG. 7 is a sectional view of the first embodiment taken along line 7—7 of FIG. 2; FIG. 8 is a perspective view of the ground engaging wear member showing my new design according to a second embodiment; FIG. 9 is another perspective view of the second embodiment; FIG. 10 is an elevational view of the second embodiment; FIG. 11 is a sectional view of the second embodiment taken along line 11—11 of FIG. 8; FIG. 12 is a sectional view of the second embodiment taken along line 12—12 of FIG. 9; FIG. 13 is a sectional view of the second embodiment taken along line 13—13 of FIG. 8; FIG. 14 is a sectional view of the second embodiment taken along line 14—14 of FIG. 9; FIG. 15 is a perspective view of the ground engaging wear member showing my new design according to a third embodiment; FIG. 16 is another perspective view of the third embodiment; FIG. 17 is an elevational view of the third embodiment; FIG. 18 is a sectional view of the third embodiment taken along line 18—18 of FIG. 15; FIG. 19 is a sectional view of the third embodiment taken along line 19—19 of FIG. 16; FIG. 20 is a sectional view of the third embodiment taken along line 20—20 of FIG. 15; and, FIG. 21 is a sectional view of the third embodiment taken along line 21—21 of FIG. 16.

Any broken line illustration of environmental structure in the drawings is not part of the design sought to be patented.
